UNITED STATES PATENT OFFICE.

DARIUS E. SHRAUGER, OF ATLANTIC, IOWA.

METALLIC WINDOW-FRAME.

1,134,642.

Specification of Letters Patent.

Patented Apr. 6, 1915.

Application filed August 25, 1913. Serial No. 786,596.

To all whom it may concern:

Be it known that I, DARIUS E. SHRAUGER, a citizen of the United States, residing at Atlantic, in the county of Cass and State of Iowa, have invented a certain new and useful Metallic Window-Frame, of which the following is a specification.

The object of my invention is to provide a metallic window frame of simple, durable 10 and inexpensive construction.

More particularly it is my object to provide a metallic window frame especially adapted to be used in an inclined roof and provided with means whereby glass panes 15 may be detachably held in proper position without the use of putty.

Still a further object is to provide in such a frame means whereby the glass holding means may be locked in position on the 20 frame, and whereby a screen may be secured to the frame for protecting the glass.

Still a further object is to provide such a screen so constructed and arranged that any water which may pass around and under 25 the glass will be carried to the lower part of the frame and discharged on the roof without passing to the interior of the building.

My invention consists in certain details, in 30 the construction, arrangement and combination of the various parts of the device, whereby the objects contemplated are attained, as hereinafter more fully set forth, pointed out in my claim, and illustrated in 35 the accompanying drawings, in which:

Figure 1 shows a top or plan view of the 40 window frame embodying my invention showing the manner in which shingles may be secured over the edges of the frame. Fig. 2 shows a vertical, sectional, detail view taken on the line 2—2 of Fig. 1, and Fig. 3 shows a vertical, sectional view taken on the 45 line 3—3 of Fig. 1. Fig. 4 is a sectional view taken on a plane parallel with that on which Fig. 3 is taken, but not cutting the clamp devices.

My improved window frame is preferably 50 rectangular in size and comprises first a flat frame which is indicated in the accompanying drawings by the reference numeral 10. At its inner edge the frame 10 is bent upwardly forming a portion 11. The portions 11, at the sides and lower end of the frame are bent over at their upper edges and then 55 downwardly forming portions 12. At their lower edges the portions 12 are bent in-

wardly forming the horizontal portions 13 which, at their inner edges, are bent upwardly forming vertical portions 14. It will be noted that the portions 12, 13 and 14 60 form channels or troughs. The portion 11, at the upper end of the frame, is bent with its upper edge inwardly toward the center of the frame, as shown in Fig. 2, then over and outwardly again to the main body of 65 the portion 11, forming a protecting shelf 15, then downwardly forming the vertical portion 12^a at the lower edge of which is a horizontal portion 13 formed on which is an upwardly extending portion 14. The 70 portions 14, 13 and 12^a form a trough or channel.

Formed in the portions 11 and 12 at the lower end of the frame, above the level of the portion 13, are drainage openings 16. 75 The channels hereinbefore described are constructed to communicate freely with each other at the corners of the frame so that any water which may get into them is quickly carried to the lower channel and 80 discharged through the openings 16.

Where it is desired to make a frame that will hold more than one pane of glass, a metal frame member is placed in position 85 comprising a sheet of metal folded at its center to form two downwardly extending walls 17. At the lower edges of the walls 17 are laterally extending portions 13 formed on which are upwardly extending portions 14. The portions 17, 13 and 14 90 form channels on each side of the central frame member similar in construction to the channels already described. The members 17 are secured at their ends to the members 12 and 12^a at the upper and lower ends of the frame, and the channels formed on said members 17 communicate at each end with the channels at the lower and upper ends of the frame.

The portions 11, 12 and 17 at the sides and 100 middle of the frame extend above the levels of the portions 11 and 12, 12^a and 15 at the lower and upper edges of the frame.

Panes of glass 18 may be placed in the 105 frame resting upon the upper edges of the walls or portions 14 of the various channels, as shown in Figs. 2 and 3. The edges of said frames are engaged at their sides by the members 12 at the sides of the frame and the members 17 of the middle frame member. At its upper end each pane is slipped 110 under the protecting shelf 15, as shown in

Fig. 2. At the lower end of the frame the members 11 and 12 are slightly higher than the member 14 and the panes of glass rest against the lower member 12 and are thereby held in position. For securing the panes of glass against being raised, I have provided the following means: At each side of the frame, I provide an engaging device comprising a vertical strip 19 which, at its upper edge, is bent over and downwardly forming a substantially vertical portion 20 above the level of the glass. Formed on the lower edge of the portion 20 is an inwardly and downwardly extending portion 21 arranged to stand out over the glass for a short distance. The portions 19 and 20 of the engaging devices are designed to receive between them the upper parts of the members 11 and 12 at the sides of the frame, as shown in Fig. 3. I provide an engaging device for holding the glass adjacent to the middle frame member which is constructed as follows: A channel 22, opening downwardly, receives the members 17 between its side walls. At the lower edges of the side walls of the channel 22 are laterally and downwardly extending portions 21 which extend outwardly and over the glass panes 18.

I preferably cover the portions of the frame which contain the glass with a screen 23 or other protecting device which rests upon the engaging devices.

For locking the engaging devices in position on the frame, and also for securing the screen 23 in position, I have provided the following means: Strips of copper 24, or other suitable material which may be readily bent and is yet stiff enough to hold the parts in position, and which will not readily rust or break when bent, are bent double and placed in substantially vertical position between the members 11 and 12 at the sides of the frame, and the members 17 at the middle of the frame. The strips 24 extend through openings 25 and 26 at the upper edges of the members 11, 12 and 17 and in the upper portions of the engaging devices, and said strips are long enough to extend beyond the portions 13 and above the engaging devices. At their lower ends, the strips 24 are bent laterally to prevent their upward withdrawal from their position when installed. The members 12, 11 and 17 are pressed together to firmly engage the strips 24. Before the engaging devices are placed in position, the upper ends of the strips 24 are arranged in practically vertical positions. After the engaging devices have been placed in position with the upper ends of the strips 24 inserted through the openings 26, the screen 23 is placed in position with the upper ends of said strips 24 inserted through the meshes in the screen. The upper ends of the strips 24 are then bent away from each other, as shown in Fig.

3, and the engaging devices and the screen will be firmly and rigidly held in position. Should a pane of glass become broken, or should it become desirable for any reason to remove the pane of glass, the upper ends of the strips 24 are bent back to their vertical position when the screen 23 and the engaging devices may be readily lifted upwardly and removed. The old pane of glass may then be removed easily and the new one inserted in its place. The engaging devices may then be replaced in position, the screen replaced and the upper ends of the strips 24 bent laterally away from each other for locking the parts in position.

My improved frame is preferably made of sheet metal and may, or may not be galvanized.

The frame members 10 may be placed on the roof around the window opening before the shingles have been laid. The shingles 30 may then be laid over the frame members 10 as shown in Fig. 1. The glass may be placed in the frame after the frame has been placed in position, and the shingles laid, if desired.

When the window is installed, it will be noted that any water falling upon the window which might pass around the edges of the panes of glass 18 would be caught in the channels hereinbefore described and conducted to the lower channel and discharged on the roof through the openings 16, thereby preventing any admission of water to the interior of the building.

My improved frame is particularly designed for use in installing windows in inclined roofs as in hog houses or other buildings used for stock. In such buildings an adequately tight joint is not so necessary as in a dwelling house. On the other hand in such buildings, it is desirable that the glass may be quickly and easily removed or replaced. In such a building where the putty of a window would be directly exposed to rain, snow and to sunlight, the putty rapidly deteriorates, cracks and falls away. Where my improved frame is used, it is unnecessary to use putty and the pane of glass can be quickly and easily placed in the window without the use of tools and without putty.

It will be understood that some changes may be made in the details of the construction of my improved window frame without departing from its essential features, and that it is my intention to cover by the following claim any such changes as may be included within the scope of the appended claim.

I claim as my invention:

A frame comprising one piece frame members having flat portions, frame members having formed thereon upwardly extending supporting portions adapted to

serve as a support for a cap and a screen, spaced downwardly extending portions formed on said supporting portions, said last described portions having upwardly 5 opening channels formed at their lower ends, adapted to support a glass pane and carry water, a protecting screen supported on said upwardly extending portions, and

clamping devices extended upwardly between said upwardly and downwardly extending portions and through said screen.

Des Moines, Iowa, August 1, 1913.
